UNITED STATES PATENT OFFICE.

WILLIAM BUNTING MORTON, OF BEATRICE, NEBRASKA.

OILCLOTH FIXTURE.

Application filed November 24, 1922. Serial No. 603,042.

To all whom it may concern:

Be it known that I, WILLIAM BUNTING MORTON, a citizen of the United States, residing at Beatrice, in the county of Gage 5 and State of Nebraska, have invented a new and useful Oilcloth Fixture, of which the following is a specification:

This invention aims to provide novel means whereby oil cloth or like material 10 may be handled readily, with a view to cutting off the oil cloth in predetermined lengths, it being unnecessary to lay down the oil cloth on a table or counter, unroll the oil cloth, measure it, and cut it in the usual 15 way.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described 25 and claimed, it being understood that, within the scope of what is claimed, changes in the precise embodiment of the invention shown can be made without departing from the spirit of the invention:

In the accompanying drawings:—

Figure 1 shows in front elevation, a device constructed in accordance with the invention; parts being broken away; Figure 2 is a top plan; Figure 3 is a side elevation; 35 Figure 4 is a vertical section on the line 4—4 of Figure 1; Figure 5 is an elevation showing a modified form of the invention, parts being broken away; Figure 6 is a bottom plan of the carrier; Figure 7 is a section on the line 7—7 of Figure 5.

In carrying out the invention, there is provided a support or cabinet 1, including ends 2 having external transverse shoulders 3, a back 4 being connected to the ends 3. Vertical finishing strips 5 may be secured 45 to the forward edges of the ends 2, the finishing strips extending upwardly to a top bar 6 secured to the ends 2, as shown at 7. A measure 8 is mounted vertically on one of the ends 2 and extends upwardly to the top bar 6. The top bar 6 is provided in its upper edge with a longitudinal groove 14, and has in its forward surface, a finger seat 15. The top 9 extends between the ends 2, and 55 between the top bar 6 and the back 4, the top 9 cooperating with the parts mentioned to

define a compartment 10 in the upper portion of the cabinet 1. The cabinet 1 may be supplied with any desired number of shelves 11.

The device includes a U-shaped frame 12 mounted for vertical swinging movement on the cabinet 1. The frame 12 embodies side arms 16, and a front bar 17 connected to the side arms by angle brackets 18 or otherwise. Pivot elements 19 connect the rear ends of the arms 16 of the frame 12 with the ends 2. When the frame 12 is in a lowered position, as shown in Figure 3, the side arms of the frame rest on the shoulders 3 of the ends 2, 76 and the front bar 17 is located above the top bar 6 of the cabinet 1. In its upper edge 6, the front bar 17 of the frame 12 is provided with a longitudinal guide way 20. A restricted slit 21 extends downwardly 75 through the front bar 17, from the guide way 20.

The device includes a trough-shaped rider 22 mounted for reciprocation in the guide way 20 of the front bar 17 of the vertically 80 swinging frame 12. An opening 23 is formed in the bottom of the rider 22. The numeral 24 marks a carrier, including a body 25 having a depending rib 26, the rib being received within the rider 22. A pivot 85 element 27 connects the rib 26 of the carrier 24 with the rider 22, the carrier thus being mounted for vertical swinging movement on the rider. The carrier 24 is swung upwardly with respect to the rider 22 through 90 the instrumentality of a compression spring 28 interposed between the bottom portion of the rider 22 and the lower edge of the rib 26 of the carrier. In one end of the carrier 24, a slit 29 is fashioned. The slit 29 receives a blade 30 extended downwardly through the opening 23 in the rider 22 and into the slit 21 of the bar 17 of the frame 12. The blade 30 has an inclined edge 31. A securing element 32 holds the blade 30 detachably assembled with the carrier, so that the blade can be removed from the carrier upon occasion, for sharpening. The spring 28 elevates the carrier 24 on the rider 22 sufficiently so that the lower end of the blade 100 30 is housed in the slit 21 of the bar 17 of the frame 12 and does not project downwardly into the groove 14 of the bar 6 which forms part of the cabinet 1. The parts are thus shown in Figures 1 and 4 of the 110 drawings.

The oil cloth or other material which is

to be severed into lengths may be stored on the shelves 11. When it is desired to cut off a length of material, the frame 12 is swung backwardly on its pivotal mounting 19, the 5 roll of material, marked by the numeral 33, is placed in the compartment 10, the free end of the roll being carried downwardly along the measure 8, until the selected length has been secured. The frame 12 is swung downwardly and forwardly into the position 10 shown in Figure 4: The carrier 24 is swung downwardly on the rider 22 until the lower end of the blade 30 enters the longitudinal groove 14 in the top bar 6. The rider 22 15 then is moved to the left (Figure 1) the edge 31 of the blade 30 cutting off the material, the material being held securely, during the cutting operation, between the top bar 6 of the cabinet 1 and the front bar 17 of the 20 frame 12.

In Figure 5 the numeral 50 marks the front bar of the vertically swinging frame, the bar 50 corresponding to the bar 17 hereinbefore described, and being provided with 25 a longitudinal slit 51. The carrier, corresponding to the part 24 is marked by the numeral 52 and includes a body 53. Guide plates 54 are attached by securing elements 55 to the sides of the body 53 and overlap 30 the front bar 50, the carrier 52 thus being mounted on the bar 50 for straight line sliding movement, longitudinally of the bar. The body 53 of the carrier 52 has a slit 56 wherein a blade 57 extends, the blade being 35 held in place by a securing element 58 such as a screw, mounted in the body 53, it being observed that one of the guide plates 53 prevents the securing device 58 from moving outwardly. The blade 57 extends downwardly 40 into the slit 51 of the bar 50 and has an inclined edge 59. Resilient tongues 60 extend longitudinally of the body 53 of the carrier 52 and are located at an acute angle to the lower surface of the body, the tongues 45 being supplied with upstanding flanges 61 through which pass securing members 62 whereby the tongues are held upon the body.

The tongues are spaced apart, as shown at 63, so that the blade 57 may extend downwardly between the tongues. The tongues 50 60 may be designated generally as a bifurcated spring, through which the blade 57 extends. In order to facilitate the sliding movement of the tongues 60 on the upper edge of the bar 50, the tongues may be inclined at one end, as denoted by the numeral 64.

It will be obvious from Figure 5 that the tongues 60 tend to hold the carrier 52 in an upwardly inclined position, the lower end of 60 the blade 57 being housed within the slit 51 of the bar 50. The operator may, however, press the body 53 of the carrier 52 downwardly, thereby flexing the tongues 60 and moving the cutting edge 59 of the blade 57 65 into an operative position, below the bar.

What is claimed is:

1. In a device of the class described, a cabinet provided in its top with a compartment for the reception of a roll of material, and including a member over which the material may be extended from the roll, a frame hinged to the cabinet and cooperating with said member to hold the material thereon, a carriage movable along the frame, and a cutter movable on the carriage, said member having a groove which receives the cutter when the cutter is moved on the carriage and when the carriage is moved on the frame. 70

2. In a device of the class described, a support; a frame mounted to move vertically on the support; a rider including a body and guides carried by the body, the guides cooperating with the frame to hold the rider on the frame for right line reciprocation; a blade carried by the rider; and a spring mounted on the carrier and slidably directly on the frame, the spring constituting means for elevating the blade. 75

In testimony that I claim the foregoing as my own, I have hereto affixed my signature.

WILLIAM BUNTING MORTON.
